COOLING APPARATUS FOR FURNACE PORTS

Edward W. Pottmeyer, Pittsburgh, Pa., assignor to
 Blaw-Knox Company, Pittsburgh, Pa., a corporation of New Jersey

Application May 2, 1945, Serial No. 591,619

9 Claims. (Cl. 122—6.5)

1

This invention relates to a furnace port cooler and, in particular, to a cooler for the port of a regenerative furnace such as the conventional open-hearth furnace.

It is an object of my invention to provide a port cooler characterized by improved circulation of cooling water therethrough and the elimination of clogging resulting from the accumulation of sediment or sludge in narrow passages, particularly between the spaced walls of the cooler and the outlet passages extending from the inner end of the cooler to the outer end. I also provide a cooler having an outlet passage between the walls thereof with sufficient sectional area to provide a substantial flow even under the rather limited pressure head available in port coolers as usually constructed.

In a preferred embodiment, the port cooler of my invention comprises a water jacket of arch section having spaced inner and outer walls with an outlet passage therebetween extending from adjacent the inner end of the cooler to the outer end, the passage having a generally rectangular section and a width several times its depth, and the depth being only approximately one-half the distance between the inner and outer walls. Conveniently, the passage is formed by a channel having its flanges welded to one of the walls, preferably the inner wall. The outlet pipe preferably has branches extending downwardly and laterally adjacent the inner end of the cooler to afford good circulation adjacent the inner end of the cooler which, of course, is subjected to the highest temperature.

For a complete understanding of the invention, reference is made to the accompanying drawings illustrating the present preferred embodiment and the following detailed description. In the drawings,

Figure 1 is a side elevation of my port cooler, partly broken away and partly in section, showing the outline of the brick work defining the port proper in chain lines;

Figure 2 is a plan view of the cooler;

Figure 3 is an end elevation such as would be seen by looking from the right in Figure 1;

Figure 4 is a transverse section taken along the plane of line IV—IV of Figure 1;

Figure 5 is a partial longitudinal section taken along the plane of line V—V of Figure 3;

Figure 6 is a partial section taken along the plane of line VI—VI of Figure 5;

Figure 7 is a partial section taken along the plane of line VII—VII of Figure 1;

2

Figure 8 is a partial elevation of the discharge end of a flushing pipe; and

Figure 9 is an end view thereof.

Referring now in detail to the drawings, the cooler of my invention comprises a water jacket 10 of arch section including spaced inner and outer walls 11 and 12, respectively. The cooler is fabricated from steel plate by welding. It is installed in a port 13 defined by brick walls adapted to deliver a mixture of preheated air and fuel to the combustion space within a furnace such as the ordinary open hearth furnace. The cooler has a shape conforming to the port, i. e., it slopes downwardly toward its inner end. A reservoir 15 in the form of a box 14 extends upwardly above the outer end of the cooler and is adapted to be supplied with water from any convenient source. The reservoir, of course, communicates with the space between the walls 11 and 12. A water level 20 is maintained in the reservoir at approximately the upper edge of a partition 15. Excess water flows over the partition into an outlet trough 16 having drain connections 17.

An outlet passage 18 extends from a point adjacent the inner end of the cooler to the outer end thereof where it communicates with the trough 16. The passage 18 is preferably formed by a channel having its flanges welded to the inner wall 11. As shown in Figures 2, 3 and 4, the channel extends along the ridge or highest portion of the inner wall 11. The passage 18 has a rectangular section and a width several times its depth. The depth, furthermore, is only approximately one-half the distance between the walls 11 and 12 so that it does not obstruct free flow of water through the space between the walls. A vent or surge pipe 19 extends upwardly from the passage 18 through the reservoir 14 above the upper edge of the partition 15.

The passage 18 preferably has a number of branches 20, 21 and 22 extending laterally and downwardly from its inner end. These passages may conveniently be defined by channels welded to the inner wall of the jacket in the same manner as that forming the passage 18. The channels forming the branches 20 and 21, as shown, are curved to conform to the arch shape of the cooler. The branches, like the main passage 18, have rectangular sections and a width several times their depth. Their depth, furthermore, is only about one-half the spacing between the walls 11 and 12. There is thus substantially no possibility of accumulation of scale or other sediment between the outer wall and the channels defining the passages, sufficient to interfere se-

riously with circulation of water through the jacket.

The course of circulation through the cooler is downwardly from the reservoir 14 along the sides and top of the cooler toward the inner end thereof from which the water flows into the branches 20, 21 and 22 and thence through the main outlet passage 18 to the outlet trough 16. Baffles 18a in the trough 16 on opposite sides of the passage 18 insure that the latter is kept filled to the extreme upper end.

Sludge, scale or other sediment accumulating in the jacket falls freely to the bottom of the sides thereof which have inwardly extending flanges 23. Flushing pipes 24 extend into these flanges and are supported on brackets 25. Slots 26 at the inner ends of the pipes discharge jets of flushing water when the pipes are connected to a suitable source thereof, whereby accumulated sediment may be washed out through holes 27 and 28 in the outer end of the cooler. These holes, of course, are closed by suitable plugs between successive flushings.

It will be apparent from the foregoing explanation that the invention is characterized by numerous advantages over port coolers as previously constructed. In the first place, the shape and disposition of the outlet passage and its branches, as already indicated, are such that they do not facilitate the accumulation of sediment between them and the outer wall so as to interfere with circulation of the cooling water. The arrangement of the outlet passage and its branches, furthermore, is also such as to create an improved circulation of cooling water. This results partly from the thermo-siphon action caused by the location of the passage 18 at the ridge of the inner wall and from its upward slope. Any sediment formed in the cooler is free to fall to the bottom of the sides from which it may be easily removed by periodic flushing. The entrances for water returning through the outlet passage 18, i. e., the lower ends of the branches 20, 21 and 22, are located closely adjacent the inner end of the cooler which is subjected to the highest temperature. At the same time, the sectional area of the outlet passage and its branches is sufficient to maintain the flow of a substantial volume of water even under the relatively low head available in the reservoir 14.

It is to be noted that while the branches 20, 21 and 22 are desirable, they may not be necessary in all cases. On the other hand, additional lateral branches from the main outlet passage 18 may be employed, if desired. These and other similar changes in the details of the construction disclosed may, of course, be made without departing from the spirit of the invention or the scope of the appended claims.

I claim:

1. A furnace port cooler comprising an elongated water jacket of arch section including spaced inner and outer walls, and means defining an outlet passage extending longitudinally of the cooler from adjacent the inner end thereof to the outer end, said passage being generally rectangular in section and having a depth approximately one-half the distance between said walls.
2. A furnace port cooler comprising an elongated water jacket of arch section including spaced inner and outer walls, and a relatively wide flat outlet passage extending along the ridge of the inner wall from adjacent the inner end of the cooler to the outer end thereof.
3. The apparatus defined by claim 1 characterized by said passage having a plurality of branches extending therefrom.
4. A furnace port cooler comprising an elongated water jacket of arch section including spaced inner and outer walls, and a relatively wide flat outlet passage between said walls from adjacent the inner end of the cooler to the outer end thereof.
5. A furnace port cooler comprising an elongated water jacket of arch section including spaced inner and outer walls, and means defining an outlet passage extending longitudinally of the cooler from adjacent the inner end thereof to the outer end, said passage being generally rectangular in section and having branches extending therefrom.
6. A furnace port cooler comprising an elongated water jacket of arch section including spaced inner and outer walls, and a channel between said walls having its flanges welded to one of them and extending from adjacent the inner end of the cooler to the outer end thereby providing an outlet passage of rectangular section having a width several times its depth.
7. The apparatus defined by claim 6 characterized by branch channels extending from said first-mentioned channel, said branch channels also having their flanges welded to one of said walls.
8. A furnace port cooler comprising an elongated water jacket of arch section including spaced inner and outer walls, and an inverted channel extending along the ridge of the inner wall from adjacent the inner end thereof to the outer end, the flanges of the channel being welded to the inner wall whereby the channel defines an outlet passage.
9. The apparatus defined by claim 8 characterized by branch channels extending from said first-mentioned channel, said branch channels also having their flanges welded to said inner wall.

EDWARD W. POTTMEYER.
